UNITED STATES PATENT OFFICE.

EVERT L. DE VALE, OF NEW YORK, N. Y.

PARING ATTACHMENT FOR KNIVES.

No. 879,857.

Specification of Letters Patent. Patented Feb. 25, 1908.

Application filed October 11, 1907. Serial No. 396,901.

To all whom it may concern:

Be it known that I, EVERETT L. DE VALE, a citizen of the United States, and residing at New York, in the county of New York and State of New York, have invented certain new and useful Improvements in Paring Attachments for Knives, of which the following is a specification, such as will enable those skilled in the art to which it appertains to make and use the same.

This invention relates to paring attachments for knives; and the object thereof is to provide an improved device of this class which may be attached to, or connected with the blade of an ordinary table or other knife, and by means of which potatoes, apples, pears and other vegetables of this class may be quickly and easily pared or peeled.

The invention is fully disclosed in the following specification, of which the accompanying drawing forms a part, in which the separate parts of my improvement are designated by suitable reference characters in each of the views, and in which:

Figure 1 is a perspective view showing my improved paring attachment for knives and one method of its operation; Fig. 2 is a side view of a knife with the attachment connected therewith; and, Fig. 3 a section on the line 3, 3 of Fig. 2.

In the drawing forming a part of this specification, I have shown a knife comprising a handle *a* and blade *b*, and the blade *b* is preferably pointed as shown at *b*²; and in the practice of my invention I provide a blade attachment *c*, composed of a sheet of metal folded centrally to form side members *c*² and *c*³, two of the latter being on the same side in the form of construction shown, and the part *c*² being on the opposite side. The folding of the sheet of metal forms a double folded portion *c*⁴, which extends longitudinally of the device and is bent laterally with reference to the body portion thereof to form a longitudinal lip adjacent to which is a longitudinal slot or opening *c*⁵, formed by cutting out the blank sheet of metal before the latter is folded; and in this operation one side part is also preferably cut out to form the side members *c*³.

The side members *c*² and *c*³ of the device form spring clamping jaws, between which in practice, the blade *b* of the knife is inserted and the separate parts of the folded lip *c*⁵ are pressed together, and when the blade *b* is inserted the edge *b*³ thereof projects slightly beyond the corresponding edge of the side member *c*² as shown at *c*⁶.

In practice all that is necessary is to insert the blade into the device *c*, or between the part *c*² and *c*³ thereof so that the lip *c*⁵ will project laterally from the blade and toward the operator, and the operation of paring or peeling a potato or similar vegetable is shown in Fig. 1.

The pointed end *b*² of the blade may be used, in practice, to take out the "eyes" of a potato, or to take out rotten specks or parts before beginning the operation of paring or peeling; but my improved paring attachment may be used in connection with the blades of different kinds or classes of knives.

My invention is not limited to the exact details of the construction shown and described, and various changes therein, and modifications thereof may be made, within the scope of the appended claims, without departing from the spirit of my invention or sacrificing its advantages.

Having fully described my invention, what I claim as new and desire to secure by Letters Patent, is:

A paring attachment for knife blades, composed of a sheet of spring metal folded centrally and longitudinally to form clamping side members between which the blade is inserted, said device being provided at the side edge thereof opposite that into which the blade is inserted with a laterally curved longitudinal lip between which and the blade when the latter is inserted is a longitudinal slot or opening.

In testimony that I claim the foregoing as my invention I have signed my name in presence of the subscribing witnesses this 10th day of October 1907.

EVERT L. DE VALE.
